(57) **CLAIM**

The ornamental design for a device for storing papers or the like, as shown and described.

DESCRIPTION

FIG. 1 is a perspective view of a device for storing papers or the like.

FIG. 2 is a front view of the device of FIG. 1.

FIG. 3 is a left side view of the device of FIG. 1.

FIG. 4 is a right side view of the device of FIG. 1; and, FIG. 5 is a top view of the device of FIG. 1.

The dotted lines are for illustrative purposes only and do not constitute any part of the claimed design.

The broken lines in FIGS. 1-5 are for environmental purposes only and form no part of the claimed design.

The “stipple” shading that can be seen in FIGS. 1, 2, and 5 is used to represent a type of surface material.
